UNITED STATES PATENT OFFICE.

AUGUST E. HENNING, OF SANTA ANA, CALIFORNIA.

AUTOMOBILE RECORDING APPARATUS.

1,269,217.

Specification of Letters Patent. Patented June 11, 1918.

Application filed October 25, 1917. Serial No. 198,438.

To all whom it may concern:

Be it known that I, AUGUST E. HENNING, a citizen of the United States, residing at Santa Ana, in the county of Orange and State of California, have invented certain new and useful Improvements in Automobile Recording Apparatus, of which the following is a specification.

This invention relates to devices for use 10 on automobiles for keeping a record of the cost of operation and maintenance of the same.

The object of the invention is the provision of a simple and inexpensive apparatus 15 of this character by which the owner or operator of an automobile can keep an accurate account of the cost of operation and maintenance of the same.

With these ends in view, the invention 20 consists in a novel construction, adaptation and combination of devices, as will be hereinafter described and claimed.

In the accompanying drawings, Figure 1 is a front elevational view of the apparatus 25 embodying my invention. Fig. 2 is an end elevational view of the same. Fig. 3 is a transverse vertical section of the same taken substantially through line 3—3 of Fig. 1. Fig. 4 is a detail section taken substantially 30 through line 4—4 of Fig. 1. Fig. 5 is an assembled view of one of the rollers and attachments in accordance with the present invention. Fig. 6 is a plan view of the writing platen. Fig. 7 is a fragmentary 35 view of the record sheet used in connection with the present invention.

Referring to the drawings, the numeral 8 designates a casing having a door 9 set in the top of the same and connected thereto, 40 as by hinge 10, and may be secured in closed position by means of knob and latch 11, the casing also has a bottom 12 (Fig. 3 and Fig. 4) and a projecting flange 13 with screw or bolt holes 14, (Fig. 1) in the same.

45 Within the casing and extending longitudinally adjacent to the door is a writing platen 44 (Fig. 3 and Fig. 6), with lug 15 on one end and lug 16 on the other end and the same is secured in slots 47 and 48 in the 50 ends of the casing by springing it into position.

Within the casing and extending longitudinally near the bottom, are a pair of slotted rollers 17 and 17' the ends of the same 55 acting as journals 19 (Fig. 5) and bearing

in circular openings or holes 20 and 20' (Fig. 2) in the ends of the casing. Each roller has fixed on it (pressed fit) a pair of guides 22 and 22' and a gear 23 and 23' (Fig. 5). Gears 24 and 24' (Fig. 4) which 60 engage respectively with the gears 23 and 23' and project through apertures 26 and 26' (Fig. 1) in the top of the casing, are mounted on shafts 25 and 25' respectively, said shafts extend longitudinally within the 65 casing below the writing platen and the ends of the same act as journals which bear in circular openings or holes 27 and 27' (Fig. 2) in the ends of the casing.

28 indicate brake blocks which are yield- 70 ingly held against guides 22 and 22' of the respective rollers by means of a spring 29 to prevent any looseness in the sheet as it is advanced in either direction in the opera- 75

A special record sheet 30 of paper is coiled about one of the rollers. The free end of 80 said sheet is passed through the interstice between the top of casing and the writing platen and thence through a slot in the other roller.

The record apparatus when in use is fitted into the cowl or instrument board of an automobile and attached to same by inserting screws or bolts through holes 14, and 85 thence into the cowl or instrument board.

The operation of the device is as follows:

The paper record sheet 30 being applied 90 to the rollers and extending in front of the writing platen 44 is advanced to the calendar month by turning one of the operating gears 24 or 24', in the proper direction with the thumb or finger; for when one gear is operated it takes up the record sheet on the roller it drives as it is drawn off the 95 other roller, the sheet is kept tense over the writing platen by the spring and brake blocks. The apparatus is then ready to receive the entries as they occur. The apparatus is opened to receive entries by turning 100 knob 11 and opening glass door 9.

The record sheet is spaced, ruled and headed to receive entries in a systematic manner for each month over a period of two years. Sample entries are shown on 105 fragmentary view of record sheet 30 (Fig. 7). Entries occur whenever any expense is incurred or money expended on or for the automobile.

The gears 24 and 24' allow the record 110

sheet to be advanced in either direction, thus permitting an examination of the record sheet whenever desired.

What I claim is—

- 5 1. An automobile record apparatus including a casing provided with a door in the top and a bottom, a pair of rollers within said casing, said rollers journaled in openings in the ends of the said casing, a pair of guides and a gear fixedly mounted on each roller, a pair of drive gears which project through separate apertures in the top of the casing and mounted on separate shafts, which are journaled in openings in 10 the ends of the said casing, said drive gears engaging with the gears on the rollers, a writing platen arranged longitudinally of and in said casing adjacent to the door, the ends of said writing platen fixed in openings provided for the same in the ends of 15 the casing.
2. An automobile record apparatus consisting of a pair of rollers with a gear fixedly mounted on each, a writing platen supported above said rollers, said rollers propelled by two gears mounted on separate shafts, which engage respectively with the gears mounted on the rollers; said pair of rollers, writing platen and drive gears all 20 contained and operating within a casing, except said drive gears which project beyond the top of the casing through openings made for the same, said casing also having a door in its top, a bottom and a surrounding flange, all substantially as described. 25
- 35

3. An automobile record apparatus including a casing provided with a door in the top, a bottom, a flange with screw or bolt holes and two rectangular apertures, each end of the casing also having a slot 40 for the support of a writing platen and four circular openings acting as bearings for two shafts and two rollers, said two rollers being provided with a pair of guides and a gear mounted on each, said two shafts 45 being provided with a drive gear mounted on each, which engage respectively with the gears on the rollers and projecting through the rectangular apertures, a writing platen and a set of brake blocks and springs, attached to the bottom of the casing, all substantially as described. 50

4. An automobile record apparatus including a casing provided with a door in its top and a bottom, a pair of rollers within 55 said casing, said rollers journaled in openings in ends of said casing and engaging with a pair of drive gears mounted on separate shafts which are journaled in other openings in the ends of said casing, said 60 drive gears projecting beyond the top of said casing through openings made for the same.

Signed in Santa Ana, in the county of Orange and State of California, this 20th 65 day of October 1917.

A. E. HENNING.
